It will thus be seen that the objects set forth above, among those made apparent from the preceding description, are efficiently attained and, since certain changes may be made in carrying out the above method and in the compounds set forth without departing from the scope of the invention, it is intended that all matter contained in the above description shall be interpreted as illustrative and not in a limiting sense.

It is also to be understood that the following claims are intended to cover all of the generic and specific features of the invention herein described, and all statements of the scope of the invention, which, as a matter of language, might be said to fall therebetween.

Now that the invention has been described, what is claimed as new and desired to be secured by Letters Patent is:

What is claimed is:

1. A dicyanoethylfattydiamine of the formula:

where $a=0$ to 2, x and y are whole numbers and $x+y=6$ to 22.

2. N,N'-di-(β -cyanoethyl) aminomethylpalmitylamine falling within the formula:

where $x+y=16$, said x and y being whole numbers.

3. N,N'-di-(β -cyanoethyl) aminomethylstearylamine falling within the formula:

$\text{CH}_2-\text{NHCH}_2\text{CH}_2\text{CN}$

where $x+y=16$, said x and y being whole numbers.

4. N,N'-di-(β -cyanoethyl) aminostearylamine falling within the formula:

$\text{NHCH}_2\text{CH}_2\text{CN}$

where $x+y=16$, said x and y being whole numbers.
